UNITED STATES PATENT OFFICE.

JEAN BAPTISTE MAURICE LIARSOU, OF PARIS, AND COLOMBAN COLOMBANI, OF BONDY, FRANCE, ASSIGNEES OF ONE-HALF TO REGINALD FORD, OF PARIS, FRANCE.

CLOSING MEANS FOR RECEPTACLES OF ALL KINDS.

1,372,007.

Specification of Letters Patent. Patented Mar. 22, 1921.

Application filed April 8, 1920. Serial No. 372,327.

To all whom it may concern:

Be it known that we, JEAN BAPTISTE MAURICE LIARSOU, of 27 Rue du Poteau, Paris, France, and COLOMBAN COLOMBANI, 5 of 46 Avenue de la Republique, Bondy, France, have invented new and useful Improvements in Closing Means for Receptacles of All Kinds; and we do hereby declare the following to be a full, clear and exact

10 description of the same.

There are already known closing means comprising capsules which by reason of the resiliency of their peripheries are fixed and maintained on receptacles having substantially cylindrical necks. Capsules of this kind, as employed in practice, possess the disadvantage, owing to the considerable force to which they are subjected in opening or closing the receptacle, of rapidly losing 15 their resilience; they become deformed and become useless more or less rapidly, the closure that they secure being not sufficiently hermetic.

The present invention has for its object 20 to provide a resilient or substantially resilient capsule adapted to fit on the mouth of a receptacle, and being shaped to insure a perfectly hermetic closure which will last almost indefinitely without becoming deformed, as the slight force required to open 25 or close the receptacle is insufficient to deform the capsule.

The capsule is preferably formed of a single piece of any suitable material and it 30 is preferably manufactured from resilient or substantially resilient metal. The capsule includes a cap having a head and a depending skirt, the latter forming an outwardly extending channel and an inwardly extending 35 continuous annular flange the lower edge portion of the skirt being restricted by spinning on a lathe, or the like, to form the inwardly extending annular beveled flange which has a continuous annular edge that grips the 40 outer surface of the receptacle and holds the cap in place. The outer surface of the receptacle near its mouth is upwardly flared to provide an enlargement which is designed to be received within the channel of the cap. 45

50 The distance between diametrically opposite

points of the annular edge of the flange is less than the distance between diametrically opposite points at the outer end of the flared surface of the receptacle in order that the edge may grip the flared surface of the 55 receptacle. In a modified form of the invention the flared portion of the receptacle is provided with two diametrically opposite flat surface which coöperate with two similarly arranged flat surfaces of the cap. An 60 elastic or plastic joint member located in the head of the capsule assures the air tightness of the closure.

A method of carrying the invention into practice is illustrated by way of example by 65 the accompanying drawings, in which:—

Figure 1 is a view of a capsule in elevation.

Fig. 2 is a section of the capsule along the line X—X of Fig. 1. 70

Figs. 3 and 4 show the method of fitting the capsule on the receptacle.

Fig. 5 shows inverted a slightly resilient capsule of a somewhat different form.

Figs. 6 and 7 show in plan and in elevation the shape of the neck of the receptacle in the case of an absolutely rigid capsule. 75

Fig. 8 shows a resilient connection for connecting the capsule to its receptacle, and

Fig. 9 illustrates the application of the 80 capsule to the closure of a so called invertible ink well.

The capsule (Figs. 1 and 2) is in the form of a cap which includes a head 1 and a depending substantially cylindrical skirt 2, the 85 lower portion 3 of which is restricted by spinning on a lathe, or the like, to form an inwardly extending annular flange having a continuous annular edge designed to engage and grip the outer surface of the receptacle with which the cap is used. The cap is preferably formed from a single piece of resilient metal. In the interior of the capsule is arranged a disk 4 of flexible material, for example of india rubber, cork, etc. 90

The receptacle 5 on which the capsule is fixed preferably includes a substantially cylindrical neck, the outer surface of the upper end of which is flared upwardly as shown at 7. The diameter of the upper 100

end of the flared surface is slightly greater than the diameter of the restricted mouth of the capsule.

The operation of this closing device is 5 as follows:—

The capsule being in place on the receptacle (Fig. 3) opening is effected (Fig. 4) as hereinafter described with one hand only and without the assistance of any instrument. This operation is effected by placing 10 two fingers on the two ends of a diameter, indicated by a marking on the neck of the receptacle, for example the diameter situated in the plane of Fig. 2, and pressing 15 with one of the fingers while with the other slightly lifting the capsule; with this movement the capsule, rocking around the diameter perpendicular to the above diameter, slides along the rim which becomes 20 disengaged on one side, and on the other lodges in the circular gallery or channel 8 formed by the body of the capsule above the restricted mouth 3, the latter no longer bearing 25 on the rim except at the two extremities of the axis of rotation. A very slight effort is sufficient to remove the capsule which, so long as it is slightly resilient, can pass over the two last points of contact with the rim.

Closing is effected by reversing the operation. The capsule is presented obliquely 30 in relation to the rim as shown in Fig. 4, and is then pushed forward to engage the rear part of the rim. The forward part of the capsule is then pressed downward, a 35 slight effort only being necessary to cause the restricted mouth of the capsule to pass over the rim at the two ends of the diameter perpendicular to the plane of the figure.

On the completion of this operation the 40 air tightness of the closure is assured by means of the disk 4 of india-rubber, leather, cork, or other similar material, which pressed forcibly against the edge of the receptacle forms a spring by reason of its 45 elasticity.

In the modification illustrated by Fig. 5 the restricted mouth of the slightly resilient capsule 9 has a slightly oval shape 10, this oval shape allowing the capsule to exercise 50 at the ends of its smaller diameter, pressure on the lower part of the rim thus adding to the effect of the disk in assuring air tightness of the closure, and if necessary allowing the joint member to be dispensed with.

55 The above described method of operation is on the assumption that the capsule possesses a certain amount of resilience, however small it may be. If it is desired to employ absolutely rigid capsules, for example of glass, it is necessary to introduce a slight modification in the shape of the rim of the receptacle. The latter (Figs. 6 and 7) is provided with a projecting circular rim 11 preferably of semi-circular 60 shape but this rim has two slight flat sur-

faces 12 and 13 diametrically opposite to each other. The diameter of the rim 11 is slightly larger than that of the restricted mouth of the capsule except at the two flat surfaces 12 and 13 where it is of the same, 70 or even of slightly smaller diameter.

The operation of this device is the same as in the case of the slightly resilient capsule. The capsule being in position (Fig. 7) opening is effected by rocking the capsule 75 about the diameter joining the centers of the two flat surfaces. This rocking is effected by placing two fingers at the two ends of the diameter indicated by a marking on the neck of the receptacle, and pressing 80 with one of the fingers while lifting the capsule slightly with the other finger; the latter slides along the rim which becomes disengaged at one side and on the other side lodges in the circular space 14 85 formed by the body of the capsule above the restricted mouth; the opening is then effected of itself, the two flat surfaces 12 and 13 allowing free passage of the capsule. Closing is effected by reversing the above 90 operations.

The two flat surfaces might equally well be formed on the mouth of the capsule instead of being formed on the mouth of the receptacle.

95 The disk 4 may instead of being shaped as a plain disk as is shown in the drawings, be formed with a circular central opening into which the pressure within the receptacle may penetrate. This arrangement allows 100 automatic tightening of the fitting to be obtained by the expansion caused by the pressure. It will be obvious that the less the capsule itself is resilient, the more it is necessary for the disk to be so.

105 To connect the capsule to the receptacle on which it is to be applied it may if desired be provided (Fig. 8) with a flexible connection constituted preferably by a metal wire 15 fixed on the one hand to the capsule and 110 on the other hand to a ring 16 comprising a part 17 forming a spring. The elasticity of this ring allows it, when being placed in position, to slip over the rim 7 of the neck so as to engage in a channel 18 formed 115 in the neck, and in which it remains in position.

120 The closure thus constituted is extremely effective; its resistance to being forced off by the pressure existing in the interior of the receptacle is very great since it can withstand up to 50 kilograms per square centimeter with a thickness of metal of 4 to 10 millimeters; the capsule is of simple and cheap construction and may be used a great 125 number of times without any depreciation on this account. This method of closure may have a considerable number of applications; for the closing of bottles and flasks of all kinds, as a lid for metal boxes, such as black- 130

ing boxes, as lubricating caps for automobiles, as stoppers for water and petrol tanks in automobiles, caps for electric switches, and for many other purposes. The use of 5 the device may be extended to the joining of two parts, for the closing of press buttons, and the joining of pipes.

A modification of the capsule applied to the closure of an invertible ink well is illustrated by Fig. 9. The capsule is then perforated at its center 19 and the edges of this perforation are extended by a cylindrical or conical part 20 which serves as a seating for the various kinds of rubber, or other funnels, flexible or rigid tubes 21 which are used 15 in such ink wells.

What we claim is:

1. Means for hermetically and instantaneously closing receptacles of all kinds, comprising in combination with the cylindrical neck of the receptacle having an annular rim projecting therefrom, of a capsule formed from a single piece of suitable material and in the form of a cap having a 20 mouth restricted into a bevel shape and of a diameter slightly less than the diameter of the rim designed for rocking engagement 25

with the opposite points of the rim whereby to consequently snugly embrace the rim, the exterior surfaces of the said neck being provided with two diametrically opposed flat faces. 30

2. The combination with a receptacle having an upwardly flared annular surface at its mouth portion, of a capsule formed from a single piece of resilient metal and having a depending skirt, the lower edge of said skirt being shaped to provide an inwardly extending continuous annular flange, the distance between diametrically opposite points of the 35 edge of said flange being less than the distance between diametrically opposite points at the upper end of the flared surfaces of the receptacle, the skirt being formed immediately above said flange with an outwardly 40 extending channel designed to receive the upper edge of the receptacle, whereby said cap may be placed on the mouth of the receptacle and the edge of the flange will grip the flared surface of said receptacle. 45 50

In testimony whereof we affix our signatures in presence of two witnesses.

JEAN BAPTISTE MAURICE LIARSOU.
COLOMBAN COLOMBANI.
